[57] CLAIM

The ornamental design for a disposable camera retainer for an archery bow, as shown and described.

DESCRIPTION

FIG. 1 is a perspective view of a disposable camera retainer for an archery bow incorporating my new design;

FIG. 2 is a reduced left elevation view thereof attached to a bow and retaining a camera;

FIG. 3 is a right elevation view thereof;

FIG. 4 is a rear elevation view thereof;

FIG. 5 is a front elevation view thereof retaining a camera;

FIG. 6 is a bottom plan view thereof; and,

FIG. 7 is a top plan view thereof.

The broken lines shown in FIGS. 2 and 5 are for environmental purposes only and form no part of the claimed design.
